UNITED STATES PATENT OFFICE

JAMES H. BOYE, OF CHICAGO, ILLINOIS, ASSIGNOR TO THE BOYE NEEDLE COMPANY,
OF CHICAGO, ILLINOIS, A CORPORATION OF ILLINOIS.

HASP.

1,078,990.

Specification of Letters Patent.

Patented Nov. 18, 1913.

Application filed July 10, 1913. Serial No. 778,288.

To all whom it may concern:

Be it known that I, JAMES H. BOYE, a citizen of the United States, residing at Chicago, in the county of Cook and State of Illinois, have invented a new and useful Improvement in Hasps, of which the following is a specification.

This invention relates particularly to hasps adapted for use in connection with barn doors or in analogous situations; and the primary object of the invention is to provide a hasp of simple construction and improved operation.

The invention is illustrated, in its preferred embodiment, in the accompanying drawings, in which—

Figure 1 represents a broken perspective view (partly in section), showing a hasp constructed in accordance with my invention, applied to a door; Fig. 2, a broken elevational view, the keeper and bolt of the hasp being shown in section; Fig. 3, a broken elevational view showing the bolt or latch contracted; Fig. 4, a view illustrating the manner in which the latch or bolt may be detached from the supporting and guiding plate; Fig. 5, a broken horizontal sectional view, showing the parts in the position indicated by full lines in Fig. 4; Fig. 6, a section taken as indicated at line 6 of Fig. 3; and Fig. 7, a section taken as indicated at line 7 of Fig. 3.

In the construction illustrated, A represents a door which is adapted to swing in the usual way, the hinges not being shown however; B a door jamb or portion of a wall; and C the improved hasp.

The hasp comprises a supporting-plate 1; a sliding bolt or latch 2 which is normally capable of limited pivotal movement; and a keeper 3. The supporting or attaching plate 1 is preferably of bar form and provided with a reduced rear end portion 1^a. It is secured to the door by screws 1^b and 1^c. Struck outwardly from the plate 1 are lugs 4, which serve as a combined guide and pivot. The lugs 4 are separated by a space, and one is turned up and the other down, thus forming flanges 4^a. The portions or

lugs which are at right angles to the plate 50 1 are rounded on their upper and lower surfaces as indicated at 4^b. This result may be accomplished by making the outstanding portions of concavo-convex form. Thus, the rounded surfaces 4^b are adapted to serve 55 as a pivot.

The member 2 partakes of the nature of a sliding-bolt and pivot-latch. It comprises a bar having a longitudinal opening or slot 5 therein, which engages the lugs 4. The 60 rear portion of the bar has its lateral edge portions struck inwardly to afford guide flanges 6 which embrace the edges of the reduced portion 1^a of the supporting-plate 1. The rear extremity of the member 2 is made 65 of half circular form and bent outwardly at right angles to the member, to form a finger-piece or ear 7. At its front end, the bar 2 is cut of a size to provide a tongue 8 and a loop 9, the loop being bent so as to project 70 outwardly at right angles to the plate 2. This leaves the tongue 8 projecting beyond the loop, and the latter are provided with latches 8^a.

The keeper 3 comprises a plate having an 75 outwardly bent extremity 3^a which is cut out to form a loop corresponding with the loop 9. The loops 3^a and 9 are adapted to receive a pad-lock. At the base of the slot 3^b of the keeper are lateral notches 3^c, the lower one 80 of which is adapted to interlock with the lower notch 8^a of the tongue 8. The distance between the bottoms of the notches 8^a is greater than the vertical measurement of the opening 3^b of the keeper, so that the 85 door can not be swung outwardly when the bolt is serving as a latch, or when the latch is lifted slightly from the position shown in Fig. 1. The depth of the notches 3^c is sufficient, of course, to enable the head of the 90 tongue 8 to enter freely. When a pad-lock is applied to the loops 3^a and 9, it is evident that the bolt is secured against retraction.

The sliding-plate 2 is provided near its advance end with perforations 10, which are 95 larger than the heads of the screws 1^c, so that when the plate 2 is retracted, as shown in Fig. 3, the screws 1^c may be inserted to

secure the plate 1 to the door. In this position of the parts, access to the screw 1^a is afforded through the slot 5. When the member 2 is projected, the securing-screws 5 are housed and concealed back of the plate 2. Thus, when the hasp is locked, it is impossible to remove the screws; and at such time the screws, which secure the keeper, are covered by the advance end of the plate 2.

10 It will be understood from the foregoing that the sliding hasp-plate 2 is normally capable of a limited turning movement about the pivot lugs 4, to enable the lower notch 8^a to enter into interlocking engagement 15 with the lower notch 8^c. Should the door have a tendency to settle, the latch-member 2 will serve to support it, it being understood that in such case the upper flange 6 will bear on the upper edge of a reduced portion 1^a of the attaching and guide plate 1, while the upper lug 4 will engage the upper wall of the slot 5.

The plates 1 and 2 may be assembled by bringing the plate 1 to the position shown by dotted lines in Fig. 4, engaging the slot 5 with the lugs 4, and then turning the plate 1 to the position parallel with the plate 2, in which action the upper flange 6 will ride over the front face of the plate 1, the plate 30 2 springing or yielding sufficiently to permit the parts to be readily assembled in this manner. By providing the upper and lower notches 8^c and 8^a, the hasp is made reversible; that is, it can be applied at either 35 vertical edge of the door.

The parts may be readily stamped from a metal strip, or from sheet-metal, and the assembling may be effected without the use of rivets, so that the device can be cheaply 40 produced.

The foregoing detailed description has been given for clearness of understanding only, and no undue limitation should be understood therefrom, but the appended claims 45 should be construed as broadly as permissible in view of the prior art.

What I regard as new and desire to secure by Letters Patent is—

50 1. A hasp of the character set forth, comprising a securing-plate provided with an outstanding projection adapted to serve as a pivot and guide, and a sliding latch-plate having an elongated slot engaging said projection and having flanges freely engaging said first-named plate thus permitting limited turning of the latch-plate about the pivot, and affording a limited vertical movement to the free end of said plate, for the purpose set forth.

60 2. A hasp of the character set forth, comprising a securing-plate equipped with an outstanding projection adapted to serve as a pivot and guide, a latch-plate having a

tongue on its free end and provided with an elongated slot engaging said projection, and 65 guide-connections between said plates at another point, permitting limited pivotal movement of the latch-plate, and affording a limited vertical movement to the free end of said latch-plate, for the purpose set forth. 70

3. A device of the character set forth, comprising a keeper having an outstanding loop and a notch at the base of the loop opening, a sliding-plate having a tongue adapted to enter the loop opening and 75 equipped with a notch to interlockingly engage said first-named notch, a supporting-plate, and guide-connections between the supporting-plate and the latch-plate enabling the plate to be reciprocated and to turn 80 to a limited extent only in use.

4. A device of the character set forth, comprising a keeper equipped with an outstanding loop having notches at the upper and lower sides of the loop opening, a latch- 85 plate having a tongue adapted to enter the loop opening and equipped at its upper and lower edges with notches, a supporting-plate, and guide-connections between the latch-plate and supporting-plate enabling 90 the latch-plate to be reciprocated.

5. A device of the character set forth, comprising a supporting-plate having a pair 95 of outstanding lugs, one of which is turned up and the other down, a latch-plate provided with an elongated slot engaging said lugs, and guide-connections between the latch-plate and the supporting-plate at another point.

6. A device of the character set forth, 100 comprising a supporting-plate equipped with outstanding lugs having rounded upper and lower surfaces and flanges projecting beyond said rounded surfaces, a latch-plate provided with an elongated slot 105 engaging said lugs, and guide flanges on one of said plates freely engaging the upper and lower edges of the other plate.

7. A device of the character set forth, comprising a supporting-plate having a pair 110 of outwardly struck, oppositely turned lugs adapted to serve as a pivot and guide, and a latch-plate having a slot engaging said lugs and having flanges engaging the upper and lower edges of said first-named plate, said 115 latch-plate having a notched tongue at one end and having also an outwardly projecting thumb-piece.

8. A device of the character set forth, comprising a keeper provided with an outstanding loop, a latch-plate equipped with a tongue adapted to enter said loop and equipped also with an outstanding loop adapted to lie adjacent said first-named loop, a supporting-plate, and guide-connections 120 between the supporting-plate and

latch-plate enabling the latch-plate to be reciprocated and to turn to a limited extent with relation to the supporting-plate.

9. A device of the character set forth, comprising a supporting-plate provided with attaching screws, and a latch-plate slidably mounted on the supporting-plate and provided with openings adapted to reg-

ister with the screws when the latch-plate is retracted, the latch-plate serving to cover 10 the screws when the latch-plate is projected.

JAMES H. BOYE.
